Primary Examiner — Leanne Was-Englehart*(74) Attorney, Agent, or Firm* — Dorsey & Whitney LLP(57) **CLAIM**

The ornamental design for a landscaping block wall, as shown and described.

DESCRIPTION

FIG. 1 is a perspective view of a landscaping block wall; and,

FIG. 2 is a front elevational view of the landscaping block wall of FIG. 1.

The broken lines in the figures depict portions of the landscaping block wall that form no part of the claimed design.
